[57] **ABSTRACT**

Aliphatic, cycloaliphatic, aromatic and heterocyclic carboxylic acid and sulfonic acid chlorides are prepared from the corresponding carboxylic and sulfonic acids and phosgene by reacting the salt-like addition compounds of the said carboxylic or sulfonic acids with N-alkyl-pyrrolidones or N,N-diethyl-carboxylic acid amides having at least 4 carbon atoms in the molecule in a polar, inert solvent with phosgene at a temperature below 0°C, at atmospheric pressure or elevated pressure, and completing the reaction by heating at a temperature of at most +30°C. The acid chlorides obtained are especially pure and without further isolation they can be used, for example, for the manufacture of polyamides.

5 Claims, No Drawings

PROCESS FOR THE MANUFACTURE OF
CARBOXYLIC ACID AND SULFONIC ACID
CHLORIDES

The present invention relates to a process for the manufacture of carboxylic and sulfonic acid chlorides of high purity by reacting phosgene at low temperature with salts of corresponding acids and dimethylacetamide, N-methylpyrrolidone, or other high molecular weight N,N-dialkylcarboxylic acid amides, optionally in the presence of suitable solvents.

It has been proposed to prepare chlorides of the aforesaid type, for example by reacting carboxylic or sulfonic acids with phosphorus trichloride, phosphorus oxychloride, phosphorus pentachloride or thionyl chloride. The reaction of the acids with phosgene has also been described in a plurality of publications. This reaction has the advantage that only gaseous by-products are formed, which can be readily absorbed or do not pollute the atmosphere. The reactions take place according to the following equations:

In Houben-Weyl, Methoden der organischen Chemie, volume IX, page 567 (1955) a process is described for reacting sulfonic acids or the alkali metal salts thereof with phosgene in an inert medium at 140° to 180°C to obtain sulfonic acid chlorides. Fatty acid chlorides with long chains can be prepared from the corresponding fatty acids and phosgene at 140° to 160°C (cf. Houben-Weyl, volume VIII, page 472 (1952)).

U.S. Pat. No. 2,657,233 provides a process for the manufacture of dicarboxylic acid dichlorides from dicarboxylic acids and phosgene under a pressure above 10 atmospheres gage and at temperatures in the range of from 100° to 250°C.

British Specification No. 540,096 discloses the manufacture of carboxylic acid chlorides from carboxylic acids having at least 10 carbon atoms and phosgene at a temperature of at least 100°C in the presence of 5% of tertiary amines.

U.S. Pat. No. 2,848,491 is concerned with the reaction of mono-carboxylic acids with phosgene at a temperature in the range of from room temperature to 200°C, preferably 90° to 200°C, in the presence of an anion exchanger.

U.S. Pat. No. 3,184,506 teaches that the continuous manufacture of carboxylic acid chlorides from carboxylic acids and phosgene is also possible at temperatures of from 50° to 125°C in the presence of 0.05 to 5% by weight, preferably 0.1 to 1% by weight, of dimethylformamide. This process is characterized in that in the reaction zone an excess of carboxyl groups must always prevail as otherwise the complex compound of dimethylformamide and phosgene decomposes and large amounts of tarry reaction products are formed.

It is the common feature of all the aforesaid processes that the reaction with phosgene is carried out at elevated temperature and partly at elevated pressure. It cannot be avoided that under these reaction conditions a series of secondary reactions take place. The reaction products obtained are thus contaminated and must be freed from the by-products simultaneously formed by expensive purification processes. In the temperature ranges required acid chlorides react, for example, with the acids used as starting products to yield

acid anhydrides with separation of HCl. With the use of nitrogen-containing catalysts undefined and colored by-products are obtained, which, especially in the case of a discontinuous process, may cause the formation of tarry deposits in the reaction vessels. The formation of such by-products could be substantially avoided if the reaction could be carried out at a sufficiently low temperature. In the known processes the reaction speed at low temperature is, however, so slow that an economic manufacture is not possible.

It has now been found that chlorides or carboxylic and sulfonic acids can be obtained in simple manner and with high purity by reacting the salts of carboxylic acids or sulfonic acids and N,N-dimethyl acetamide, 15 N-methyl-pyrrolidone, or other N,N-dialkyl carboxylic acid amides having at least 4 carbon atoms, optionally dissolved in acetonitrile, or other polar inert solvents, with phosgene at a temperature of from -20° to 0°C and completing the reaction by heating at a temperature of at most +30°C. The reaction takes place very quickly and with a high yield according to the following equations:

To prepare the salt-like compounds from carboxylic acids or sulfonic acids N,N-dimethyl acetamide, N-methyl-pyrrolidone, or other N,N-dialkyl carboxylic acid amides having at least 4 carbon atoms can be used, for example tetramethyl-urea, whereas the lowest representative of this class the N,N-dimethyl formamide is unsuitable because of the very low yield obtained therewith.

50 The salt-like compounds from the acids and dimethyl acetamide need not be prepared in a separate reaction and isolated in substance. Preferably, equimolecular amounts of the components can be used in the phosgenation. The salts of carboxylic acids or sulfonic acids and dimethyl acetamide, N-methyl-pyrrolidone, or other higher N,N-dialkylcarboxylic acid amides are often sparingly soluble only in the chosen solvent, but a very low solubility is already sufficient to start the reaction.

55 Besides acetonitrile, other polar solvents or diluents that can be mixed with water or are readily soluble in water can be used, provided that they are inert to the reactants at the reaction temperatures. Solvents of this type are, for example, propionitrile, tetrahydrofuran, glycol dimethyl ether, and diglycol dimethyl ether.

60 The ratio of amide salt to acetonitrile or another polar diluent can vary in the range of from 1 : 0.8 to 1

: 2.0, preferably 1 : 1.2 to 1 : 1.6 parts by weight. It is also possible to operate without a special diluent, provided that an excess of the N-alkyl-pyrrolidone or N,N-dialkyl-carboxylic acid amide required for the formation of the salt-like addition compounds is used.

When carrying out the process of the invention the reaction temperatures should be kept so low that no secondary reactions of the phosgene or the acid chlorides with the nitrogen-containing salt forming agents or the free acid may occur. The reaction temperatures are in the range of from -30° to +30°C, preferably, however from -20° to +20°C. According to a preferred embodiment of the process of the invention phosgene is introduced at low temperature, for example about -15°C, and the reaction is then completed by heating, for example to +20°C. At temperatures exceeding 30°C continuously decreasing yields of the desired acid chlorides are obtained.

For each equivalent of the carboxyl group or sulfonic acid group 1.0 to 1.5 equivalents, preferably 1.1 to 1.2 equivalents of phosgene are used. The phosgene can be added in dosed quantities at atmospheric pressure or at elevated pressure. Sulfonic acids often contain crystal water, but the hydrates may also be used if one mole of phosgene and two moles of the nitrogen containing salt forming agent are additionally used to bind one mole of crystal water.

With discontinuous performance of the process of the invention the termination of the reaction can be perceived by the end of the CO₂ separation. When a suspension is used for phosgenation, the formation of a clear solution likewise indicates the end of the reaction. In the latter case, it must be kept in mind, however, that following the reaction proper there may often occur a precipitation of hydro-chlorides of dimethyl acetamide or the other corresponding compounds. Depending on the introduction rate of the phosgene, the reaction time is in the range of from 1 to about 5 hours.

Prior to working up the reaction mixture by distillation it is necessary to remove the formed hydrochlorides of the nitrogen containing compounds, for example of dimethyl acetamide, as these substances react with the acid chlorides at elevated temperature. To remove the hydrochlorides the reaction mixture can be diluted with a non polar solvent for example benzene, whereupon the hydrochloride crystallizes out and can be filtered off. Thus, the compounds used as salt forming agents and catalysts can be recovered. If necessary, last traces of the amide hydrochlorides can be eliminated by rapidly washing with cold water the reaction solution diluted with an inert solvent.

The reaction solutions obtained in the process of the invention can be directly used for further reactions without further treatment or purification of the acid chlorides. It is thus possible to produce unsaturated and/or temperature sensitive acid chlorides and directly to use the reaction solutions obtained for further reactions. The reaction solutions can be reacted, for example, with amines, alcohols or phenols. They are also suitable for the manufacture of polyamides, for example by the process disclosed in German Pat. No. 1,420,681, without isolating the acid chlorides obtained.

In the process of the present invention the following carboxylic and sulfonic acids can be used:

1. aliphatic, cycloaliphatic, aromatic and heterocyclic mono-, di- and polycarboxylic acids possibly

carrying substituents which do not react at the chosen reaction temperatures with the acid chlorides or phosgene, such as, for example, acetic acid, chloroacetic acid, propionic acid, acrylic acid, butyric acid, crotonic acid, cyclohexane-carboxylic acid, adipic acid, sebacic acid, cyclohexane-1,4-dicarboxylic acid, benzoic acid, toluic acid, naphthalene-carboxylic acids, halogenated benzoic acids, isophthalic acid, terephthalic acid, trimellitic acid, nicotinic acid, quinoline-carboxylic acid, indole-3-carboxylic acid, pyrazine-2,3-dicarboxylic acid;

2. aliphatic, cycloaliphatic and aromatic mono- and disulfonic acids possibly containing further substituents which are inert to sulfonic acid chlorides and phosgene at low temperatures, for example methane-sulfonic acid, ethane-disulfonic acid, butane-sulfonic acid, β -chlorethane-sulfonic acid, cyclohexane-sulfonic acid, benzene-sulfonic acids, toluene-sulfonic acids, p-chloro-benzene-sulfonic acids, naphthalene-sulfonic acids, benzene-1,3-disulfonic acid, naphthalene-disulfonic acids, pyridine-3-sulfonic acid.

The following examples illustrate the invention, the parts and percentages being by weight unless otherwise stated.

EXAMPLE 1

61 Parts of benzoic acid were dissolved in a mixture of 49.5 parts of N-methyl-pyrrolidone and 200 parts by volume of aceto-nitrile. The solution was cooled to -15°C with the exclusion of moisture and at a temperature in a range of from -10° to -15°C 60 parts of phosgene were introduced within about 30 minutes. When the introduction was terminated, the solution was stirred for about 15 minutes at -15°C. Next, the reaction mixture was heated to about +20°C within the course of 2 hours. During this period of time considerable amounts of CO₂ were split off. The reaction mixture was stirred for a further hour at 20°C and diluted with 2,000 parts by volume of benzene or toluene. The solution was filtered, rapidly washed with a total amount of 500 parts by volume of ice-water, dried and concentrated. At a temperature of 64° - 65°C under 12 mm Hg 59.7 parts (85 % of the theory) of benzoyl chloride were obtained by distillation of the residue.

EXAMPLE 2

166 parts of isophthalic acid were mixed with 174 parts of N,N-dimethyl acetamide and 500 parts by volume of acetonitrile. By heating at about 60°C a homogeneous solution was obtained. On cooling the salt of 1 mole isophthalic acid and 2 moles of dimethyl acetamide crystallized out. At -10°C 220 parts of phosgene were introduced into the mixture with the exclusion of moisture within the course of 1 hour. The mixture was then heated to +20°C during the course of 1 hour. A yellowish solution formed with splitting off of CO₂. Stirring of the solution was continued for 2 hours at +20°C, whereupon it was diluted with 4,000 parts by volume of benzene. The reaction mixture was allowed to stand for a short while, the separated dimethyl acetamide hydrochloride was separated and the acid chloride solution was rapidly washed with about 1,000 parts by volume of ice-water. The solution was dried, concentrated and the residue subjected to fractional distillation. At 102° - 104°C under 1.5 mm Hg 191.5 parts (94 % of the theory) of isophthaloyl chloride distilled off.

When the reaction was carried out at +70°C, the yield of isophthaloyl chloride was only 45.5 % of the theory.

EXAMPLE 3

110 Parts of phosgene were introduced within 1 hour at -12°C into a mixture of 83 parts of isophthalic acid, 99 parts of N-methyl-pyrrolidone and 250 parts by volume of acetonitrile. The mixture was allowed to warm up to +20°C and at that temperature the mixture was stirred until the splitting off of CO₂ was terminated and a clear solution had formed. After dilution with 2,000 parts by volume of benzene only little N-methyl-pyrrolidone hydrochloride separated. The filtered solution was rapidly washed with 500 parts by volume of icewater and worked up as usual. 99.5 Parts (98 % of the theory) of isophthaloyl chloride were obtained in a purity of 99.9 %, determined by gas chromatography.

EXAMPLE 4

83 Parts of isophthalic acid were dissolved in 500 parts by volume of dimethyl acetamide by heating to 70°C. The colorless substance which crystallized out on cooling to -15°C was filtered off with suction, washed with ether and carefully dried. 94.8 Parts (55.8 % of the theory) of a salt of 1 mole of isophthalic acid and 2 moles of dimethyl acetamide having the summation formula C₁₆H₂₄N₂O₆ were obtained. The decomposition point of the compound was found to be 82°C.

A mixture of 170 parts of the salt and 200 parts by volume of acetonitrile was reacted at -10°C with 110 parts of phosgene. After working up under the conditions of the preceding examples, 85.6 parts (84 % of the theory) of isophthaloyl chloride were obtained.

EXAMPLE 5

A mixture of 83 parts of the terephthalic acid, 99 parts of N-methyl-pyrrolidone and 250 parts by volume of acetonitrile was reacted at -10°C within 1 hour with 115 parts of phosgene. A clear almost colorless solution was obtained from which CO₂ separated on heating to +20°C. The solution was stirred at 20°C until the separation of CO₂ was terminated (about 90 minutes) and diluted with 1,500 parts by volume of benzene. The benzenic solution was rapidly washed with icewater, dried, concentrated and the residue was distilled. At 129° - 130°C under 10 mm Hg 87.2 parts (86 % of the theory) of terephthaloyl chloride melting at 83°C were obtained.

EXAMPLE 6

In the manner described above a mixture of 83 parts of terephthalic acid, 87 parts of dimethyl acetamide and 300 parts by volume of acetonitrile was reacted with 110 parts of phosgene. After termination of the reaction a solution of 87 parts of dimethyl acetamide in 100 parts of methanol was dropped into the reaction mixture. The temperature rose to 50°C. After having been allowed to stand for 1 hour at about 25°C, the reaction mixture was poured on ice. The crystalline precipitate was filtered off with suction, washed and dried. 63 Parts (65 % of the theory) of terephthalic acid dimethyl ester melting at 141°C were obtained.

EXAMPLE 7

118 Grams of phosgene were introduced at -13°C into a mixture of 128 parts of cyclohexane-carboxylic

acid, 87 parts of dimethyl acetamide and 300 parts by volume of acetonitrile. The reaction mixture was heated to 20°C and stirred at that temperature for 1 hour. The mixture was then diluted with 2,000 parts by 5 volume of benzene and the precipitated dimethyl acetamide hydrochloride was filtered off. The filtrate was subjected to fractional distillation by means of a column having a good separation power. 97.6 parts (66.6 % of the theory) cyclohexane-carboxylic acid chloride 10 were obtained at 61°C under 7 mm Hg.

EXAMPLE 8

95.1 Parts of p-toluene-sulfonic acid monohydrate 15 were dissolved in a mixture of 130.5 parts of N,N-dimethyl acetamide and 300 parts by volume of acetonitrile, the solution was cooled to -10°C and at that temperature 110 parts of phosgene were introduced during the course of about 1 hour. The mixture was stirred for 30 minutes at -10°C, the temperature was 20 raised to +20°C within 2 hours and the mixture kept at that temperature for another 2 hours. Considerable amounts of CO₂ separated. The mixture was diluted with benzene, the dimethyl acetamide hydrochloride was filtered off, the filtrate was rapidly washed with a small amount of icewater and concentrated. The residue was distilled under reduced pressure. 88.6 Parts (93 % of the theory) of p-toluene-sulfonic acid chloride melting at 69°C distilled over at 135° - 136°C under 10 mm Hg.

When the reaction solution diluted with benzene was not washed with icewater, the yield of p-toluene-sulfonic acid dichloride amounted to 86 % of the theory.

EXAMPLE 9

In the manner described in Example 6, 95.1 parts of p-toluene-sulfonic acid monohydrate, 148.5 parts of N-methyl-pyrrolidone and 300 parts by volume of acetonitrile were reacted with 113 parts of phosgene. 89.6 Parts (94 % of the theory) of p-toluene-sulfonic acid chloride boiling at 109° - 110°C under 2 mm Hg were obtained.

EXAMPLE 10

25 Parts of p-toluene-sulfonic acid monohydrate 50 were dissolved in 100 parts by volume of N,N-dimethyl acetamide and benzene was added to the solution until it became turbid. The separating crystals were filtered off with suction, washed with benzene and dried. 22.5 Parts (62 % of the theory) of colorless crystals were obtained which started to decompose at 73°C. It was the p-toluene-sulfonic acid dimethyl acetamide salt of the summation formula C₁₁H₁₇NO₄S.

A mixture of 129.5 parts of the salt with 200 parts by volume of acetonitrile was reacted at -12°C with phosgene in the manner described above. After the usual working up, 75 parts (79 % of the theory) of p-toluene-sulfonic acid chloride were obtained.

EXAMPLE 11

73 Parts of adipic acid, 87 parts of N,N-dimethyl acetamide and 200 parts by volume of acetonitrile were 65 reacted at -12°C with 112 grams of phosgene. The reaction mixture was allowed to warm up to +21°C whereby CO₂ was split off. The mixture was diluted

with 2,000 parts by volume of benzene and the dimethyl acetamidehydrochloride was filtered off with suction. The filtrate was concentrated in a thin layer evaporator. From the residue a further portion of dimethyl acetamide hydrochloride separated, which was filtered off. The filtrate was distilled and 52.1 parts (57 % of the theory) of adipic acid dichloride were obtained at a boiling point of 97°C under 2 mm Hg.

EXAMPLE 12

86 Parts of crotonic acid, 87 parts of dimethyl acetamide and 250 parts by volume of acetonitrile were reacted at -10°C with 108 grams of phosgene. The reaction mixture was heated to +20°C whereby CO₂ was split off. The mixture was stirred for about 2 hours at +20°C, diluted with 2,000 parts by volume of benzene and the dimethyl acetamide hydrochloride was filtered off with suction. The filtrate was washed with icewater, dried and concentrate. By distillation of the residue 58.5 parts (56 % of the theory) of crotonic acid chloride were obtained at 124°C under 760 mm Hg.

EXAMPLE 13

72 Parts of acrylic acid were dissolved in 87 parts of dimethyl acetamide and 300 parts by volume of acetonitrile and at -12°C 108 parts of phosgene were introduced into the solution obtained, which was then heated to +20°C under the separation of CO₂ was terminated. At a temperature of from 0° to +10°C, 190 parts of aniline were dropped into the reaction solution, stirring was continued for about 30 minutes at +20°C, the mixture was poured into water and filtered. After washing and drying, 128 parts of acrylic acid anilide melting at 105°C were obtained.

EXAMPLE 14

During the course of 90 minutes a solution of 123 grams of pyridine-3-carboxylic acid (nicotinic acid) in 600 milliliters of dimethyl acetamide was reacted at -10°C with 120 grams of phosgene. The reaction was

completed by heating the reaction mixture to +20°C for a short while. The reaction solution was again cooled to -10°C and 219 grams of diethyl amine were dropped in at that temperature within 20 minutes. The reaction mixture was heated at +20°C and allowed to stand for some hours at that temperature. The dark brown reaction solution was poured into water, sodium hydroxide was added and the mixture extracted with benzene. The benzene phase was dried and concentrated. By fractional distillation 125.5 grams of nicotinic acid diethyl amide were obtained in the form of a yellowish oil at a temperature of 125° - 126°C under 0.8 mm Hg.

What is claimed is:

1. A process for the manufacture of a carboxylic acid chloride from the corresponding carboxylic acid and phosgene, which comprises reacting the salt-like addition compound of an aliphatic, cycloaliphatic, aromatic or heterocyclic carboxylic acid having 1 or 2 hetero nitrogen atoms with an N-alkyl-pyrrolidone or an N,N-dialkyl-carboxylic acid amide having at least 4 carbon atoms in the molecule, in a polar, inert solvent present in weight ratio of 0.8:1 to 2.0:1 to said salt like addition compound, with 1.0 to 1.5 molar equivalents of phosgene based upon said carboxylic acid at a temperature from -30°C to +30°C, at atmospheric pressure or elevated pressure and completing the reaction by heating the reaction mixture to at most +30°C.

2. The process of claim 1, wherein the reaction temperature is in the range of from -20 to +20°C.

3. The process of claim 1, wherein the inert solvent is acetonitrile.

4. The process of claim 1, wherein an excess of the N-alkyl-pyrrolidone or N,N-dialkyl-carboxylic acid amide used for the formation of the salt-like addition compound is used as inert solvent.

5. The process of claim 1, wherein N-methylpyrrolidone or N,N-dimethyl acetamide is used.
